UNITED STATES PATENT OFFICE.

AUGUST W. REILING, OF FORT WAYNE, INDIANA.

TRAIN-CONTROLLING DEVICE.

1,048,880.

Specification of Letters Patent. Patented Dec. 31, 1912.

Application filed February 6, 1911. Serial No. 606,670.

To all whom it may concern:

Be it known that I, AUGUST W. REILING, a citizen of the United States, residing at Fort Wayne, in the county of Allen and State of Indiana, have invented new and useful Improvements in Train-Controlling Devices, of which the following is a specification.

My present invention relates to train controlling devices and particularly to improvements in the devices covered by my Patent Number 895,109, dated August 4, 1909, in which the operation of a valve on the air brake system on the train is electrically controlled by the closing of a normally open electric circuit, the closing of the circuit being accomplished by the contact of devices on the train with a third rail, or other track contact, and by the closing of an electric switch by an attendant.

I have found that it would be better practice to make use of a normally closed circuit in order that the attendant shall be required to close the switch to permit the train to pass by, and the object of my present invention is to provide novel means for maintaining a closed electric circuit at a predetermined point on the track and to enable the current to be effective on the train braking devices at that point.

It consists in the novel features herein-after described and illustrated in the drawings in which—

Figure 1 is a diagrammatical view of a locomotive provided with the contact shoe, the air release valve and controlling magnet and circuit, the rail and third rail, all as described in my former patent above referred to, and also my present invention as applied thereto; Fig. 2, a sectional view of the track, third rail and case, which case contains the closed circuit producing devices and circuits therefor; Fig. 3, an enlarged vertical section of the closed circuit producing devices and circuit therefor and Fig. 4, a side elevation of the valve and its actuating means.

Referring to the drawings, 1 is the locomotive or other car to which my invention is to be applied.

2 are the rails of the track and 3 a suitable third rail or track contact which extends parallel with one of the rails a suitable distance in the vicinity of a tower or other building in which an operator is stationed.

A suitable contact shoe or brush 4 is suitably supported on the locomotive or car and is adapted to make contact with the third rail. Within the cab or other suitable part of the locomotive or car is a release valve 5 which is connected to a pipe connection 6 which communicates with the air line 7 of the air brake system of the locomotive or car. Valve 5 comprises a casing 5' having an opening or port 8 which leads to atmosphere, and within the casing is a valve 9 which is adapted to normally seat therein to close communication between connection 6 and atmosphere. A lever 10 is pivotally mounted on the casing 5' having one arm projecting above valve 9, a spring 11 being positioned between the projecting arm and casing 12 which casing is carried by casing 5'. The lower or depending arm of lever 10 is provided with a notch 13 which is adapted to engage latch 14. Latch 14 is pivoted to a housing or casing 15 and passes within the same. Casing 15 is carried by the lower extremity of valve casing 5'. Beneath latch 14 and within casing 15 is fixed an electro-magnet 16 having an armature 17 which, when the magnet is energized, will be elevated and strike latch 14, thereby causing lever 10 to rock on its pivot and release valve 9. Spring 11 therefore rocks the lever on its pivot causing it to depress valve 9 to establish communication between connection 6 and atmosphere. A suitable adjustable stop 18 serves to control the movement of lever 10 in order to control the movement of valve 9, so as to control the exhaust of the air. Magnet 16 is connected on one side by wire 19 with one of the axles 20 of the car and, on the other side by wire 21 with contact shoe or brush 4.

At a convenient point, preferably adjacent the track, is provided a housing 22 within which is mounted an electro-magnet 23, one side of which is connected by wire 24 to third rail 3 and the other side of which is connected by wire 25 to binding post 26 mounted on the top of the same and by wire 27 to one pole of battery 28. Armature 29 passes into magnet 23 in the usual manner and is adapted to be elevated when the magnet is energized. A pin 30 in the bottom of the magnet passes loosely through flange 31 on the lower end of armature 29 and serves to prevent rotation of the armature during its movement. On the top of

magnet 23 are arranged two contact plates 32, 33, which are suitably connected as by wires, 34, 35 to binding posts 26 and 36 respectively. The upper portion or half of 5 armature 29 is formed of brass or other suitable material which will not be attracted by electric current, and suitably secured to the upper end of the armature as by screw 37 is a spool 38 having a winding 39 thereon. Spool 38 carries two contact plates 40, 41, which are adapted to make contact with contacts 32, 33, and to which the ends 42, 43 of winding 39 are respectively connected. Contacts 32, 33 and 40, 41 may be of any 10 desired form to close by their contact the circuit between connections 34, 35, which contact is established and maintained by gravity and broken by the upward movement of armature 29. Coil 39 has a greater 15 resistance than the resistance of winding 23 and acts as a shunt coil or resistance between binding posts 26, 36. Binding post 36 is connected by wire 44 to one of the rails 2 of the track and by wire 45 to the 20 pole of battery 28 opposite to that to which binding post 26 is connected by wire 27. A switch 46 is connected by wires 47 and 48 to wires 27 and 45 respectively in order to provide a short circuit for battery 28. The 25 battery and switch will be situated in the operator's tower where the same will be easy of access by him.

The operation of my invention is as follows: Assume that no locomotive or car 30 makes contact with third rail 3. The several track devices and circuits are therefore in their normal position and condition; that is, switch 46 is open, winding 23 is inactive, armature 29 is down thereby causing contacts 40 and 41 to engage contacts 32, 33 and close the circuit from one pole of battery 28 through wire 27, binding post 26, connection 34, contacts 32 and 40, shunt winding 39, contacts 41 and 33, connection 35, binding post 36 and wire 45 to the other pole of battery 28. There is therefore a normally closed circuit through shunt coil 39 at all times. If a train is approaching third rail 3, and the operator desires to permit 40 it to proceed, he closes switch 46, thereby short circuiting the battery through wires 27 and 47, the switch and wires 48 and 45. The current in the battery is therefore of no effect to energize magnet 23 or magnet 16 on 45 the valve, and the train may continue its journey unmolested. If the operator desires the train to stop or has not for any reason closed switch 46 and the same remains in its normal unopen position the following takes 50 place as soon as contact shoe or brush 4 makes contact with third rail 3. The circuit between the third rail and one rail of the track is completed by the brush 4 and the wheel of the car, the circuit thus established being from third rail 3, through wire

24, magnet 23, wires 25 and 27, battery 28, wires 45 and 44, rail 2, the wheel and axle of the car, wire 19, through magnet 16, wire 21, to brush 4. This circuit is possible since the resistance of the winding on magnet 23 is less than that of shunt winding 39. The current flowing in the latter circuit energizes magnet 23 to cause armature 29 to rise and break the connection between contacts 32 and 40 and 41 and 33, thereby disconnecting 70 the shunt coil 39 and permitting all the current to pass through the latter circuit. The current flowing in this circuit energizes magnet 16 which elevates armature 17 and releases latch 14 from engagement with lever 10. Lever 10 is therefore free to rock on its pivot under the influence of spring 11 to open valve 9 more or less according to the outward movement of the depending arm of the lever as limited by adjustable stop 18. 75 By adjusting stop 18 a mere signal may be given to the driver of the car or an ordinary train stop release of pressure may be produced which will set the brakes on the train or car and thereby stop the train as 80 is ordinarily done, or an emergency release of pressure may be produced which will bring the train or car to a sudden stop, which can be released by the operator in his 85 tower by closing his switch 46.

The third rail may be as long as may be desired and situated at any desired point or points on the track, and the train or car is under the complete control of the operator in the tower at all times, while the train or car is within his reach, which control is only limited by the length of the third rail. By placing a third rail on each side of the tower the operator may stop the train or car before it reaches the tower or catch it after it has 100 passed the tower.

What I claim is:

1. The combination with an energizing source of electricity and means to short circuit the same, of a track, a third rail, an electro-magnet, an electric circuit including the energizing source, the track, the third rail and the electro-magnet, the circuit being normally open at the track and third rail, means connected in shunt with the circuit to normally close the circuit, a car having means thereon to close the circuit at the normally open terminals whereby the electro-magnet is energized to disconnect the normally closing means for the purposes 110 115 120 described.

2. The combination with an energizing source of electricity of a track, a third rail, a circuit connecting the track and third rail and normally open between said track and rail, a car having means thereon adapted to close the circuit, means adjacent the track and connected in shunt with the circuit for normally closing the same, an electro-magnet connected in the circuit and having its 125 130

- armature connected to the shunt means, the electro-magnet being so connected in the circuit as to be energized when the car closes the circuit and disconnect the shunt means from the circuit, and means to short-circuit the energizing source.
3. The combination with an energizing source of electricity and means to short-circuit the same, of a track, a third rail, an electro-magnet adjacent the track, an electric circuit including the energizing source, the track, the third rail and the electro-magnet, the circuit being normally open at the track and third rail, a shunt winding on the armature of the electro-magnet removably connected in the circuit for normally closing the same, and a car having means thereon to close the circuit at the normally open terminals whereby the electro-magnet is energized to disconnect the shunt winding for the purposes described.
4. The combination of a circuit comprising a track, a third rail, an energizing source of electricity and an electro-magnet adjacent the track, the circuit being normally open at the track and third rail, a shunt winding on the armature of the electro-magnet and removably connected to the circuit for normally closing the same and means to close the circuit at the normally open terminals whereby the electro-magnet is energized to disconnect the shunt winding from the circuit.
5. The combination with a track and third rail, of an electro-magnet adjacent the track having a shunt winding on its armature, a battery, an electric circuit including the battery, the track, the third rail and the electro-magnet, the circuit being normally open at the third rail and track, two contact plates, one being connected to one side of the circuit and the other to the other side, means on the shunt winding to make sliding contact with said contacts for normally closing the said circuit, and means to close the circuit at the track and third rail whereby the battery current energizes the electro-magnet which disconnects the shunt winding from the circuit, for the purposes described.

In witness whereof I hereunto subscribe my name.
